UNITED STATES PATENT OFFICE.

HENRY W. GILLETT, OF NEWPORT, RHODE ISLAND.

DESIGN FOR A DENTAL SEPARATOR.

SPECIFICATION forming part of Design No. 28,934, dated June 28, 1898.

Application filed May 28, 1897. Serial No. 638,631. Term of patent 14 years.

To all whom it may concern:

Be it known that I, HENRY W. GILLETT, a citizen of the United States, residing at Newport, in the county of Newport and State of Rhode Island, have invented and produced a new and original Design for Dental Separators, of which the following is a specification, reference being had to the accompanying drawing, forming a part thereof.

10 The figure is a diagram view of the separator, showing my new design enlarged several times.

As shown in the drawing, the design consists in a body having an angular shape C and 15 rounding surfaces A and B, with a small spirally-grooved waist D. The cylindrical up-

per portion A has the flat top and the beveled bottom shown, and the central portion has a similar shape, but oppositely placed, with its beveled portion extending upward with the 20 intermediate waist between.

The design also comprises the cube-like figure C, outlined upon the extension D.

Having described my invention, what I claim as new, and desire to secure by Letters 25 Patent, is—

The design for a dental separator, as herein shown and described.

HENRY W. GILLETT.
